UNITED STATES PATENT OFFICE.

IMOGEN N. THOMAS, OF TROY, NEW YORK.

DESIGN FOR A CARBONATOR.

45,511.

Specification for Design.

Patented Mar. 24, 1914.

Application filed October 5, 1912. Serial No. 724,224. Term of patent 14 years.

To all whom it may concern:

Be it known that I, IMOGEN N. THOMAS, a citizen of the United States, residing at Troy, Rensselaer county, New York, have invented a new, original, and ornamental Design for Carbonators, of which the following is a specification, reference being had to the accompanying drawing, forming part hereof.

In the drawing Figures 1 and 2 are re-

spectively a front and a rear view of a carbonator, showing my new design.

I claim:

The ornamental design for a carbonator, as shown.

IMOGEN N. THOMAS.

Witnesses:

GEO. L. COOPER,
MINNIE J. REEVES.
